UNITED STATES PATENT OFFICE.

CHARLES H. MYERS, OF CLIFTON SPRINGS, NEW YORK.

THILL-ADJUSTER.

SPECIFICATION forming part of Letters Patent No. 278,449, dated May 29, 1883.

Application filed October 27, 1882. (No model.)

To all whom it may concern:

Be it known that I, CHARLES H. MYERS, a citizen of the United States, residing at Clifton Springs, in the county of Ontario and State of New York, have invented certain new and useful Improvements in Thill-Adjusters; and I do hereby declare the following to be a full, clear, and exact description of the invention, such as will enable others skilled in the art to which it appertains to make and use the same.

My invention relates to thill-adjusters; and it consists of an improved thill-adjuster, in combination with wrenches of different sizes and a hammer-head.

The object of my invention is to furnish these various tools in a more compact and convenient shape and at a less cost than heretofore.

When the parts constituting my invention are properly united together, they form a thill-adjuster with lever-power for forcing the thill-eye into place against the resistance offered by a spring or rubber anti-rattler when one is used. When the parts are used after being separated they supply the need of two wrenches, often required to be used at the same time, or a hammer and wrench, together or separately. Thus my invention becomes very useful both to carriage makers and owners, and is a valuable "companion" for the carriage and all such vehicles.

This novelty can be made of steel or wrought-iron or very cheaply of cast-iron; but I prefer to use malleable iron in its construction.

The more fully to understand my invention, reference may be had to the accompanying drawings, which form a part of this application.

Figure 1 represents my invention in perspective with the various devices combined to form a thill-adjuster.

The letter A represents a lever, jointed at B to an arm, C, which is bent upward at a right angle at I. In this upright part a slot, E, is made to admit the end of the yoke of the clasp on the lower rear side of the axle. The slot E', wide enough to receive the lever A, is formed by extending the sides of the arm C, which extensions c c are flattened vertically to admit eyes for a bolt or key, which passes also

through an eye in the lever, joining the two together. The working-point F' of the lever A is made of any desired shape, so that it will rest firmly upon the thill-iron when in the act of coupling. There should be several eyes made through the lever A, to allow such an adjustment of the parts as will adapt it to thill-couplings of different sizes. While an ordinary bolt and nut or equivalent fastening may be used to connect these parts together, one that can be quickly inserted or withdrawn is desirable; and I prefer to use as a very cheap and effective fastening a key represented in the drawings by Fig. 2, D representing the body or shank of the key. At one end of this key I make a side projection, a, and at the other end, on the same side, form a weight, H. In using this key the eyes B in the extensions c c of the arm and in the lever A have grooves b, adapted to admit the projection a of the key. These eyes and grooves are made to coincide laterally only when the arm C is dropped to a position shown by the dotted line C'. Then the key, with the projections turned upward or toward the lever-point, may be easily inserted or removed. On turning the key after its insertion it remains in place, the weight H preventing it from turning back and working out while in use. I also form a wrench on the arm C at K, and one at L, and another at N on the lever A. These wrenches may be of various sizes. A hammer-head is also placed at P, strengthening the joint and serving the purposes of a hammer. After forcing the eye of the thill into place and inserting the retaining-bolt, two wrenches are often required to tighten up the nut on the bolt—one to hold the bolt-head and the other to screw up the nut. These tools are supplied at once by withdrawing the key D from the thill-adjuster and simultaneously applying the wrenches formed on the lever and arm before mentioned. The utility of the hammer attachment, either alone or with a wrench, is too evident to require explanation.

Having thus described my invention, what I claim, and desire to secure by Letters Patent, is—

In a combined thill-adjuster, wrenches, and hammer, the combination of the lever A, hav-

ing wrench-heads L and N, the hammer-head P, point F, and grooved eyes B B, with the arm C bent at a right angle, and having slots EE', the extensions cc', with flattened ends, the 5 grooved eyes B B in said flattened ends, and the wrench-head K on the bent part of the arm C, and the gravity-key D for joining the said arm C to the lever A, all adapted to be used to-

gether or separately, substantially as and for the purposes herein set forth.

In testimony whereof I affix my signature in presence of two witnesses.

CHAS. H. MYERS.
